SAFETY GUARD

Nathan Siegel, San Francisco, Calif., assignor to
Granat Bros., San Francisco, Calif., a corpora-
tion of California

Application April 1, 1947, Serial No. 738,643

4 Claims. (Cl. 63—3)

1

This invention relates to safety guards for the prevention of accidental loss of jewelry such as bracelets or necklaces worn upon the person.

An object of the invention is to provide a flexible guard attachment, designed to span a separable fastener or catch, which will serve to preserve continuity of a looped element such as a bracelet or necklace associated with the fastener should the sections of the latter become separated.

Another object of the invention is to provide a sturdy, although lightweight and comparatively inconspicuous guard of the character described.

A further object of the invention is to provide a device of the nature referred to designed for simplicity of attachment to any of the types of jewelry specified, or the like, by anyone not necessarily possessed of even ordinary mechanical skill.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to the drawing:

Figure 1 is a perspective view of a bracelet type article of jewelry showing the safety guard attached to the band thereof.

Figure 2 is a proportional, enlarged front elevational view of the safety guard and the band immediately adjacent the fastener showing the action of the guard in the event of separation of the band.

Figure 3 is an enlarged side elevational view of the guard, portions of the view being broken away so as to condense it and the mounting clips being shown, respectively, in open and closed positions.

Although many fasteners used to releasably connect the associated sections of bracelets, necklaces and the like are reasonably secure when new, extended or rough usage may wear, loosen or spring the parts so that shock or strain thereafter imposed on the fastener may cause the latter to open or separate resulting in loss of the jewelry without the immediate knowledge of the wearer. So-called "safety-fasteners" have been evolved in circumvention of such losses but wear or structural damage may render such devices not entirely incapable of accidental opening or

2

separation with the possible loss of the valuable. The safety guard of my invention is designed to circumvent such losses and is so simple in structure and manner of application as to permit anyone to very quickly attach it to an existing jewelry article.

In the form of the invention, which I have chosen to illustrate in the drawing, I provide a link or member 4 of flexible material, such as cord or the chain shown, provided at its ends with attached metallic mounting clips 6 which, in the illustrated case, may be soldered or otherwise suitably secured to the chain. The clips are substantially C-shaped in form being provided with an open gap 7 at one side thereof defined by relatively spaced and confronting end portions 8 of the clip. The cross-sectional shape of the strip making up the clip is quite important since although the latter is comparatively small and is designed to be rather inconspicuous, the strength of the clip against forces which might tend to separate the portions 8 and thereby open or enlarge the gap 7 should be of a maximum permissible value. I may embody flexion resistance into the clip in one of a plurality of ways such as by forming it from stock having a substantially solid triangular shape but I prefer to use a strip of flat thin sheet stock which is die-pressed into V-shaped cross-sectional pattern to impart the desired rigidity to the element. The degree of inflexibility however is made only great enough so that it will not be a strenuous task for a person to squeeze the clip by the use of pliers or a similar tool and thereby bring the portions 8 together to narrow or close the gap 7. By deforming the clips to form closed loops about elements of bracelets and the like at opposite ends of the usually provided separable fastener 9, the safety guard may be secured in position bridging the fastener. Of course the clips 6 should be so positioned that enough slack will be left in the flexible member 4 to permit separation of the fastener elements far enough to permit the band to be slipped over the wearer's hand or other portion of the body upon which the band is being worn.

As shown in Figures 1 and 2 the cord type of band 11 used with ladies' wrist watches 12 has become quite popular and deservedly so since it is light in weight, fairly inconspicuous and incapable of forming deep and long-lasting impressions in the skin of the wrist such as a metallic link band is capable of producing. The guard of my invention is particularly applicable to such cord bands as was described above and if the clips 55 are securely attached at points spaced slightly

from the ends of the fastener the guard will function to prevent loss of the watch, as shown in Figure 1 if, due to abrasion, constant flexing or accidental release of the cords from the means clamping them to the fastener, the cord should break or the loop should open, as it is often liable to do, at the point indicated by the numeral 13. The application of the guard to such a band is a relatively simple task and may be readily accomplished by mechanical devices such as pliers or the like. It will be noted in Figure 3 that the primary shape of the clip in its open condition is such that when the latter is squeezed in the act of securing it to the band 11 the hooked end portions 8 will be naturally bent inwardly to close the gap 7 and to bring the portions 8 well into the crevise between the adjacent cords thereby substantially surrounding the cords and enhancing the security of attachment of the clip to the cords.

I claim:

1. A guard, in combination with a bracelet comprising a band of flexible compressible material having open ends and latching means on said open ends, said guard comprising a flexible member, a clip of deformable compressible material on each end of said flexible member each clip being constructed and adapted for gripping and compressing said material of the bracelet adjacent to but entirely independently of the latching means on said bracelet open ends.

2. A guard, in combination with a bracelet comprising a band of flexible compressible material having open ends and latching means on said open ends, said guard comprising a flexible member, a clip of deformable material on each end of said flexible member each clipping constructed and adapted for gripping and com-

pressing said material of the bracelet adjacent to but entirely independently of the latching means on said bracelet open ends.

3. A guard, in combination with a bracelet comprising a band of flexible compressible material having open ends and latching means on said open ends, said guard comprising a flexible member, a C-shaped clip of deformable compressible material on each end of said flexible member each clip being constructed and adapted for gripping and compressing said material of the bracelet adjacent to but entirely independently of the latching means on said bracelet open ends.

15 4. A guard, in combination with a bracelet comprising a band of flexible compressible material having open ends and latching means on said open ends, said guard comprising a flexible member, a C-shaped clip of deformable material on each end of said flexible member each clip being constructed and adapted for gripping and compressing said material of the bracelet adjacent to but entirely independently of the latching means on said bracelet open ends.
